CLAIM

The ornamental design for a display screen or portion thereof with graphical user interface, as shown and described.

DESCRIPTION

FIG. 1 is a front view of a first embodiment for a display screen or portion thereof with graphical user interface.

FIG. 2 is a front view of a second embodiment for a display screen or portion thereof with graphical user interface; and, FIG. 3 is a front view of a third embodiment for a display screen or portion thereof with graphical user interface.

The broken outer peripheral lines of the figures illustrate a display screen or portion thereof and form no part of the claimed design. The remaining broken lines in the figures illustrate portions of the graphical user interface that form no part of the claimed design.

1 Claim, 3 Drawing Sheets
